UNITED STATES PATENT OFFICE.

ANDRÉ BUSTANOBY, OF NEW YORK, N. Y.

DESIGN FOR A BOTTLE.

SPECIFICATION forming part of Design No. 36,764, dated February 2, 1904.

Application filed January 6, 1904. Serial No. 187,986. Term of patent 3½ years.

To all whom it may concern:

Be it known that I, ANDRÉ BUSTANOBY, a citizen of the United States, residing in the borough of Manhattan, city, county, and State of New York, have invented a new, original, and ornamental Design for a Bottle, of which the following is a specification.

Figure 1 of the accompanying drawings is a plan of a bottle, showing my new design; and Fig. 2 is an elevation thereof.

I claim as my invention and desire to secure by Letters Patent—

The new, original and ornamental design for a bottle as shown.

ANDRÉ BUSTANOBY.
